UNITED STATES PATENT OFFICE.

JUDSON E. WAGONER, OF MONONGAHELA, PENNSYLVANIA, ASSIGNEE TO COMBUSTION ENGINEERING CORPORATION, OF NEW YORK, N. Y., A CORPORATION OF NEW YORK.

MECHANICAL STOKER.

1,354,357.

Specification of Letters Patent. Patented Sept. 28, 1920.

Application filed April 19, 1918, Serial No. 229,424. Renewed July 24, 1920. Serial No. 322,782.

To all whom it may concern:

Be it known that I, JUDSON E. WAGONER, a citizen of the United States, residing at Monongahela, county of Washington, State of Pennsylvania, have invented a certain new and useful Improvement in Mechanical Stokers, of which the following is a full, clear, and exact description.

My invention relates to mechanical stokers having grate-bars actuated by rocking-bars, and has for its object to produce a stoker in which the thrust on the piston in actuating the rocking-bars is in a line well below the plane of the axes of the rocking-bars and approaching the axis of the piston rod. Where two rocking-bars are employed located in a plane above the piston-rod and in planes on the two sides thereof the thrusts on the piston rod are with my construction practically balanced and the resultant thrust is so near the axis of the piston-rod as to relieve the same of much undesirable side thrust.

My invention also has for its object to provide means for varying the angle through which the rocking-bars are actuated and consequently the distance the grate-bars are moved thereby.

Another object of my invention is to provide means whereby the limits of movement of the grate-bars can be varied, so that the relation of the inner ends of the movable grate-bars to the side of the retort at the end of either their outward or inward movements can be changed as desired.

The following is a description of an embodiment of my invention, the embodiment being particularly designed to be incorporated in a stoker of the general type shown in U. S. Patent No. 818,010, granted to W. R. Wood, April 7, 1903, reference being had to the accompanying drawings, in which,

Figure 1 shows a longitudinal section of a stoker embodying my invention on the line $z-z$ Fig. 2, and

Fig. 2 is a transverse sectional view, the left-hand part being a section on the line $y-y$ Fig. 1 and the right-hand part being a section on the line $x-x$ Fig. 1.

Referring more particularly to the drawings, 1 is a hopper discharging fuel into the receiving end of a retort chamber 1', having sides 2 and a movable feed plate 3. 4 is one of a series of movable hollow grate-bars

alternating with stationary hollow grate-bars 5. These grate-bars have their inner ends 6 extending over the tops of the sides 2 and supported thereby, and their outer ends 7 supported on a longitudinally extending member 8. 9 are the ordinary dump grates located below the outer ends 7 of the bars 4 and 5. 10 are rocking-bars supported at their ends in bearings 11 carried by a partition 12, which has a portion 13 separated from the central portion of the rocking-bars 10 by a small clearance so as to produce substantially an air seal along the lower portion of the rocking-bars 10 so that air forced into the chamber 14 will be fed partly through the twyer openings 4' in the grate-bars and will be forced partly through the hollow grate-bars so as to discharge through ports 4² into the chamber 15 from whence it passes upward between the grate-bars 10 in a manner well understood. 70 The rocking-bars 10 are provided with projections 10² which are embraced by lugs 4² on the grate-bars 4 so that an oscillation of a bar 10 causes a reciprocation of the grate-bars 4. Below the feed plate 3 is a cylinder 16 containing a piston 17 from which extends a piston-rod 18 to which is connected a depending member 19 rigidly connected to the feeding plate 3 and carrying a cross-head 20 in which is mounted a cross-bar 21. 35 To the forward end of each of the rocking-bars 10 is connected a beveled gear 22. Mounted in suitable bearings 23 carried by the side plates 2 of the retort are segmental gears 24. Connected to each of these segmental gears is a depending lever or crank arm 25. The lower ends of these depending levers or crank arms are connected to the crossbar 21 by links 26 having turn-buckles 27, so that their lengths may be adjusted. 95 The crank arms 25 are provided with a series of perforations 25² so that the links 26 may be connected thereto at any one of a number of points, thus permitting the variation of the effective lever arm of the levers 25. By changing the connection of links 26 to the lever arms 25 the throw of the lever arms for any given movement of the piston-rod 18 can be varied so as to vary the angular movement of the rocking-bars 10 and the reciprocating movement of the movable grate-bars 4, the lengthening of the effec-

5 tive lever arms resulting in a smaller movement of the grate-bars for a given movement of the piston 17. By adjusting the 10 lengths of the links 26 by the turn-buckle 27, the other connections remaining the same, the angular position of the rocking-bars 10 can be varied so as to change the 15 position of the inner ends 6 of the movable grate-bars with reference to the side walls 20 of the retort for any given position of the piston-rod 18, a shortening of the links resulting in drawing the grate-bars 4 inward.

15 The construction shown with its adjustable features not only permits of the adjustment of the length of the throw of the 20 grate-bars 4 and of their positions for any given position of the piston 18, but results in bringing the thrust upon the piston-rod 18 in operating the rocking-bars 10 into a 25 plane lying well below the feed plate 3 and approaching the plane of the axis of the piston-rod 18. Since the lever arms 25 depend 30 downwardly in planes located upon the two sides of the piston-rod 18 and the links 35 26 lie in a plane well below the feed plate and approaching the axis of the piston-rod 19, the individual thrusts upon the piston-rod 18 resulting from the operation of the individual crank arms 25 are substantially balanced and produce a resultant thrust 40 which is in a line approximating the axis of the piston-rod 18. The invention therefore provides for the adjustments above referred to and eliminates to a large extent objectionable side thrusts upon the piston-rod 18 45 and its bearings in the cylinder head.

50 In operating the device the piston 17 is caused to reciprocate by admitting and discharging a supply of suitable fluid, thereby causing the reciprocation of the feed plate 3 and at the same time the rocking of the 55 crank arms 25 and gear 24, which results in the oscillation of the rocking-bars 10 and the longitudinal reciprocation of the movable grate-bars 4, such movements of the grate-bars resulting in the moving of fuel in the manner described in Wood Patent No. 818,010, above referred to, and at the same time fuel is supplied through the hopper 1 and the retort chamber by the movement of the feed slide 3.

55 As will be evident to those skilled in the art, my invention permits of various modifications without departing from the spirit thereof or the scope of the appended claims.

What I claim is:

1. The combination of a rocking-bar, 60 grate-bars actuated thereby, a piston and a cylinder therefor each having its axis parallel to said rocking bar, connecting means

between said piston and rocking-bar comprising an oscillating lever, means for varying the effective length of said lever, and means for adjusting the connecting means between said rocking-bar and piston so as to 65 change the angular position of said rocking-bar in relation to any given position of the piston.

2. The combination of a rocking-bar, 70 grate-bars actuated thereby, a piston-rod and cylinder therefor each having its axis parallel to said rocking bar and located in a plane below said rocking-bar, a gear upon 75 said rocking-bar, a gear meshing with said first mentioned gear, a lever connected to said second gear and extending downwardly toward the horizontal plane passing through said cylinder and connected to said piston-rod.

3. The combination of a rocking-bar, 80 grate-bars actuated thereby, a piston-rod and cylinder therefor each having its axis parallel to said rocking bar and located in a plane below said rocking-bar, a gear upon 85 said rocking-bar, a gear meshing with said first mentioned gear the axes of said gears being at right angles, a lever connected to said second gear and extending downwardly toward the horizontal plane passing through said cylinder, and a link 90 connecting said lever and piston-rod and adjustable so as to vary the effective lever arm of said lever.

4. The combination of a rocking-bar, 95 grate-bars actuated thereby, a piston-rod and cylinder therefor each having its axis parallel to said rocking bar and located in a plane below said rocking-bar, a gear upon 100 said rocking-bar, a gear meshing with said first mentioned gear the axes of said gears being at right angles, a lever connected to said second gear and extending downwardly toward the horizontal plane passing through said cylinder, and a link 105 connecting said lever and piston-rod, said link being adjustable in length.

5. In a mechanical stoker, the combination of a retort, a reciprocating feed plate therein, rocking-bars on the two sides of 110 said retort, a piston-rod and cylinder each having its axis parallel to said rocking bars and located below said retort and feed plate, a connection between said piston-rod and plate, gears upon said rocking-bars, 115 gears meshing with said first mentioned gears and provided with depending lever arms, and means located below said feed plate and connecting said lever arms to said piston-rod.

JUDSON E. WAGONER.
